PORTABLE PHONOGRAPH

Dominick F. Sementa, Basking Ridge, N.J., assignor to
International Telephone and Telegraph Corporation,
Nutley, N.J., a corporation of Maryland

Filed Apr. 1, 1965, Ser. No. 84,561

Term of patent 14 years

(Cl. D56—4)

FIG. 1 is a left side, top and front perspective view of a portable phonograph, showing my new design in closed position;

FIG. 2 is a left side, top and front perspective view, to an enlarged scale, with the hinged end speakers partly opened and the pivoted top tray partially rotated;

FIG. 3 is a left side, top and front perspective view, to the same scale as FIG. 2, with the hinged end speakers fully opened and the pivoted top tray rotated 180 degrees from the closed position; and

FIG. 4 is a rear elevational view thereof, to a reduced scale, with the pivoted top tray in closed position and the hinged end speakers fully opened.

The dominant features of my new design are shown in solid lines in the drawing figures.

I claim:

The ornamental design for a portable phonograph, substantially as shown and described.
